Theodore N. Sneed, St. Louis, Mo.

Application January 11, 1954, Serial No. 28,444

Term of patent 14 years

(Cl. D34—5)

FIG. 1.

FIG. 2.

FIG. 3.

To all whom it may concern:

Be it known that I, Theodore N. Sneed, a citizen of the United States and a resident of St. Louis, Missouri, have invented a new, original, and ornamental Design for a Carrousel-Type Amusement Device, of which the following is a specification, reference being had to the accompanying drawing, forming a part hereof.

Fig. 1 is a top plan view of a carrousel-type amusement device, showing my new design;

Fig. 2 is a side elevational view thereof, looking upwardly in Fig. 1; and

Fig. 3 is another side elevational view thereof, looking at the left side in Fig. 1.

I claim:

The ornamental design for a carrousel-type amusement device, substantially as shown.
